UNITED STATES PATENT OFFICE.

EDGAR H. HEATH, OF CHICAGO, ILLINOIS.

ATTACHMENT FOR WARP-KNITTING MACHINES.

No. 891,217.

Specification of Letters Patent. Patented June 16, 1908.

Application filed June 29, 1906. Serial No. 323,984.

To all whom it may concern:

Be it known that I, EDGAR H. HEATH, a citizen of the United States, residing at Chicago, in the county of Cook and State of Illinois, have invented certain new and useful Improvements in Attachments for Warp-Knitting Machines, of which the following is a specification.

This invention relates to improvements in that class of knitting machines in which reciprocating or shifting thread-guide bars are used, and the improvements which form the subject matter of this application pertain to the means for locking the bars in their adjusted positions.

The especial object of my invention is to provide easily operated devices which will positively lock the thread guide bars against endwise movement after each shifting operation, thus avoiding the accidental displacement of the bars which sometimes occurs where they are locked merely by frictional engagement.

For the purpose of this application for patent, I have shown and will describe only so much of a knitting machine, as is germane to my invention, it being understood that it is applicable to any form of knitting machine in which thread-guide bars are employed.

In the accompanying drawing which forms a part of this application:—Figure 1 shows in elevation a portion of the frame of a knitting machine with my improvements applied thereto. Fig. 2 is a side view of the locking means which constitute my invention. Fig. 3 is a sectional view on an enlarged scale of the locking-pin and adjacent parts.

Referring to the details of the drawing, A represents the portion of the frame of a knitting machine which supports the elements forming my invention.

H is a shaft which is journaled in suitable bearings on the frame A and which may be driven in any approved manner.

G is a cam mounted on and rotating with the shaft H, and formed with concentric cam-faces g^1 and g^2 .

B represents three thread-guide bars of common form which are slidably arranged in the plate b^3 in the usual manner. To the upper side and near the end of each guide bar is secured a plate b^1 in the face of which are formed notches b^2 .

Secured to the frame A is a plate C which is provided with a boss or thickened portion c^1 . This portion c^1 is drilled vertically to

provide suitable openings for locking pins D, and to form recesses c^2 at the upper end of such openings, and the upper edge of the boss is cut away as at c^4 .

The lower ends of the pins D are pointed or beveled to fit accurately the recesses b^2 , and the upper ends are provided with flat heads d^2 . Surrounding each of the pins within the recess c^2 is an expansion coil-spring d^2 one end of which bears against the head d^2 and the other end against the boss c^1 , so that the normal action of the spring is to lift the pin out of the notches b^2 .

Journaled in bearings c^3 on the plate C is a rocking shaft E, on the outer end of which is secured a lever F. On the lower end of this lever is a lug f^2 which frictionally engages the periphery of the cam G, thus effecting the operation of the lever. On the inner end of the shaft E is secured a plate e^1 which is formed with a horizontal extension e^2 which is adapted to rest in the cut-out portion c^4 of the plate C. This extension is provided with threaded openings to receive set-screws e^3 the lower ends of which are adapted to bear down on the heads d^2 of the locking-pins D when the parts are in the position shown in Fig. 3. A lock nut e^4 is preferably mounted on the upper end of the set-screw e^3 . The plate e^1 being fixed on the shaft E, will be rocked with the latter, through the action of the cam G on the lever F, thus causing the set-screw e^3 to alternately bear down upon and release the pin D, depending upon the relative positions of the lug f^2 on the periphery of the cam, as will be readily understood. By adjustments of the set-screw, the vertical movements of the pin will be controlled, and when the parts are in the positions shown in Fig. 3, the pin will be positively locked in one of the notches b^2 and will be so held until the cam-face g^2 is brought, through the rotation of the cam, opposite the lug f^2 .

The means for operating the locking-plate e^1 may be varied to suit the construction and operation of the different types of machines employing thread-guide-bars, hence I do not wish to be limited to the exact means shown. I am aware that in this art, coöperating notched bars and centering pins are not new, but so far as I am advised, the pins have been held in frictional contact with the bars by yielding means which do not positively lock them in place, hence, through the jarring of the machines incidental to use, the pins

sometimes get out of place with resulting damage to parts of the machine or to the fabric being knitted or to both.

Having thus described my invention, what I claim, is:—

1. In a knitting machine having adjustable notched thread guide-bars, means for locking said bars, consisting of pins adapted to engage the notches in said bars, and means for positively locking said pins in such engagement.
2. In a knitting machine having adjustable notched thread-guide bars, means for locking said bars, consisting of pins adapted to engage the notches in said bars, means for positively locking said pins in such engagement, and means for releasing the pins from such engagement.
3. In a knitting machine having adjustable notched thread-guide bars, means for locking said bars, consisting of pins adapted to engage the notches in said bars, means for positively locking said pins in such engagement, and means for automatically releasing the pins from such engagement.

4. In a knitting machine having adjustable notched thread guide-bars, means for locking said bars, consisting of pins adapted to engage the notches in the bars, adjustable means for limiting the movements of said pins, means for positively locking said pins in engagement with said bars, and means for releasing the pins from such engagement.

5. In a knitting machine having adjustable notched bars, means for locking said bars, consisting of vertically moving pins adapted to engage the notches in the bars, means for controlling the extent of the vertical movements of the pins, means for positively locking the pins in engagement with said bars, said means comprising a locking plate common to all of said pins, a rocking-shaft secured to said plate, a lever secured to said shaft and a cam for operating said lever.

In testimony whereof I affix my signature in presence of two witnesses.

EDGAR H. HEATH.
